UNITED STATES PATENT OFFICE.

CHARLIE C. HICKAM, OF PORTSMOUTH, VIRGINIA.

ENVELOP.

1,358,846.

Specification of Letters Patent. Patented Nov. 16, 1920.

Application filed April 22, 1919. Serial No. 291,841.

To all whom it may concern:

Be it known that I, CHARLIE C. HICKAM, a citizen of the United States, residing at Portsmouth, in the county of Norfolk and 5 State of Virginia, have invented certain new and useful Improvements in Envelops, of which the following is a specification.

This invention relates to mailing envelops and more particularly to improvements in 10 the safety type, the primary object of the invention being to provide an envelop which when once sealed, cannot be opened without detection or without mutilation of one or more of the flaps of the envelop. 15 A further object of the invention is to provide an envelop of this type which may be readily and conveniently sealed and which if desired may be placed upon the market partly sealed so as to render it more 20 convenient for the purchaser to complete the sealing thereof.

In the accompanying drawings:

Figure 1 is a perspective view of the envelop embodying the invention;

25 Fig. 2 is a longitudinal sectional view on the line 2—2 of Fig. 1;

Fig. 3 is a similar view on the line 3—3 of Fig. 1;

30 Fig. 4 is a plan view of the blank from which the envelop is formed.

The envelop comprises a front 1, a back 2, a closure flap 3, and end flaps 4. The front 1 is of the usual form and the back 2, closure flap 3, and end flaps 4 are integral 35 with the edges of the said front as is ordinarily the case. The envelop is formed up from the blank shown in Fig. 4 of the drawings and in order that an understanding may be had of the invention I will first de- 40 scribe the construction of the several parts of the envelop and then describe the manner in which the envelop is folded up from the blank.

The back 2 near each lateral edge is 45 formed with an incision 5 defining a sealing tongue 6 the connected end of which is located next adjacent the respective lateral edge of the said back and upon the inner face of each of these sealing tongues there is 50 provided an adhesive area 7, a similar area 8 being provided along each lateral marginal portion of the inner face of the back and the said face of the back being further provided with continuations 9 of the adhesive areas 8 which continuations extend 55 inwardly from the outer corners of the said

back for a short distance along the outer marginal portion of the back. These extension areas 9, however, are not of greater length than the width of the respective 60 end flaps 4 for a reason which will be presently explained. The back 2 is also formed with a transverse incision 10 located midway between its lateral edges and between the incisions 5 which provide the sealing 65 tongues 6.

The closure flap 3 is formed with an incision 11 providing a sealing tongue 12 having applied upon its inner face an area of adhesive 13, the attached end of the tongue being located next adjacent the outer margin of the said flap and the said tongue being located relatively close to the flap. The incision 10 and the line of union of the tongue 12 with the flap 3 are so located that in the 70 75 folded condition of the blank these two parts will be brought into registration. There is also provided upon the inner face of the sealing flap 3 adhesive areas or zones 14 and 15 extending respectively along the outer 80 marginal portion of the flap and the lateral marginal portions thereof. Each end flap 4 is formed with an incision 16 extending longitudinally thereof and parallel to the lines of fold between these end flaps and the 85 lateral edges of the front 1 of the blank, these incisions 10 and the lines of union of the sealing tongues 6 with the back 2 being so located that in the folded condition of the 90 blank these parts also will register.

In forming up the envelop from the blank the end flaps 4 are first folded in against the inner face of the front 1, the back 2 being then folded to position against the outer faces of the said end flaps. Before the back 95 is brought to this position the adhesive areas 7 are moistened and as the back is folded to the position stated the sealing tongues 6 are inserted through the respective incisions 16 and are folded back from the interior of the 100 envelop so that their moistened adhesive areas or zones will lie against the inner faces of the respective end flaps 4. Either at this time or prior to folding up the said back, the adhesive areas or zones 8 and their extensions 9 are moistened and after the sealing tongues have been inserted through the incisions in the end flaps, the back is pressed against the end flaps so as to 105 secure these parts together in the relation 110 stated. Inasmuch as the extensions 9 of the adhesive zones 8 are no longer than the

widths of the respective end flaps 4, no adhesive from these extensions will come into contact with the contents of the envelop. The foregoing steps in the forming up of the envelop from the blank may be performed by the purchaser or this work may be done in the factory so that when the envelop reaches the purchaser it will be sealed or completed except for the closing down and sealing of the closure flap 3. Prior to folding down this flap and after the matter to be transmitted has been placed within the envelop, the adhesive area or zone 13 is moistened as are also the adhesive areas or zones 14 and 15. The flap is then folded down and as this is done the sealing tongue 12 is inserted through the incision 10 being folded back in the meantime so that its adhesive area 13 will come into contact with the inner face of the back 2 of the envelop. When the envelop has been closed in the manner stated, it will be so effectually sealed that it cannot possibly be opened without detection as for example by mutilation of one or another of the flaps or the back or front thereof. The envelop embodying the invention presents a decided advantage inasmuch as after inserting the tongues 6 or the tongue 12 through their respective incisions and sealing the tongues firmly in place, it is possible

to turn back the marginal portions of the back and closure flap, respectively, sufficiently far to permit of moistening of the adhesive areas 8 and 9 and the areas 14 and 15 so that it is not necessary to moisten these adhesive areas prior to inserting the sealing tongues through their respective incisions and thus the fingers of the person sealing the envelop are not liable to become gummed through contact with these moistened areas. 40

Having thus described the invention, what is claimed as new is:

A safety envelop comprising a front, a back, end flaps, and a closure flap, the end flaps having incisions and the back having 45 tongues spaced inwardly from its margin and insertible through the said incisions, the said back having a marginal adhesive area to confront the end flaps when the envelop is closed, the said back having an incision 50 and the said closure flap having a tongue spaced inwardly from its margin and insertible through the last mentioned incision, the said closure flap having a marginal adhesive area to confront the outer face of the 55 back when the envelop is closed and being of a width to extend over and cover the first mentioned incisions and sealing tongues.

In testimony whereof I affix my signature.

CHARLIE C. HICKAM. [L. s.]
